GRINDING MACHINE

Original application filed November 10, 1928, Serial No. 318,327, and in Germany November 28, 1927.

Divided and this application filed December 28, 1929. Serial No. 417,051.

Our invention relates to a machine for the manufacture of knives, such as safety razor blades, and more particularly to a blade-sharpening or grinding machine designed to carry out the method disclosed and claimed in our co-pending application Ser. No. 318,327 of which the present application is a division.

An object of our invention is a machine which will produce a razor blade having a perfectly sharp and acute edge and which will not in the course of the grinding or sharpening operation generate any ridge which would necessitate a cumbersome treatment for removal subsequent to the grinding operation proper. Another object of our invention is a blade-sharpening machine of improved efficiency and accuracy of operation.

20 The process of sharpening knives, particularly razor blades, which has generally been in use prior to our invention, involves the necessity of removing the ridge from the edge after the latter has been ground. After 25 such removal, however, dull spots remain on the edge in dependence upon the thickness of the ridge and a subsequent polishing treatment is required to sharpen said dull spots in order to obtain a sharp edge which is ready 30 for use. Our invention permits of materially reducing this polishing step which does not only involve a material time consumption, but affects the curvature of the edge faces in the immediate proximity of the edge in an 35 unfavorable manner with the result that the edge is less sharp than it would be with a uniform curvature throughout the entire area of the ground faces.

Our invention permits the generation of a 40 sharp edge free from any ridge as a result of the grinding operation, so that no ridge at all comes to existence during the sharpening process. Hence, the edge may be finished with a very slight polishing treatment 45 which does not adversely affect the sensitive edge.

From the foregoing it will be appreciated that with our novel grinding machine the sensitive edge is carefully preserved from injury and that the edge in case it should be

injured may be completely re-generated in a simple manner.

Our invention is based upon the following consideration: When a work piece is subjected to the operation of grinding or cutting tools the latter exert, as a rule, a pressure on the material operated upon. Where they operate upon a thin edge of the work piece, the marginal zone of said edge which on account of its reduced thickness is unable to resist the pressure, will yield and will be pressed back from the edge to form a ridge which is no longer subjected to the tool and, therefore, is not removed. The conditions which account for the formation of a ridge, are always prevailing in the marginal zone of a sharp edge, the rear face of which is in an acute angle to the front operated on by the cutting or grinding tool as is the case with knives or similar work pieces. It follows 70 that the formation of a ridge can be prevented by providing a support for the marginal zone which supports the latter against the pressure exerted by the tools.

Our invention is based upon the use of such a blade support which is in intimate contact with the rear face of the edge, preferably throughout the entire area of the same up to the very edge, during the course of the grinding process whereby any yielding of the marginal zone and, consequently, the formation of any ridge is avoided. In other words, we support the rear face of the edge in the course of the grinding process, preferably over its entire length, at least up to the line determining the final situation of the cutting edge of the blade so that the support is partly ground away together with the blade bearing against it. In this regard our invention differs from the prior art in which the support bearing against the rear face was not ground off together with the blade.

In the drawings we have illustrated a preferred embodiment of our novel grinding machine which is particularly well adapted for carrying out our method of sharpening razor blades forming the subject-matter of the aforementioned application.

In Fig. 1 we have shown a side view of the machine; Fig. 2 is the top view and Fig. 3

is a perspective partial view of the machine, the part situated to the left of line $\alpha-\alpha'$ of Fig. 1 being broken away. Fig. 4 illustrates a razor blade and Fig. 5 is a diagram indicating the successive stages of the method of operation.

The frame 1 is provided with a horizontal guide slidably accommodating a carriage 3, having upwardly projecting arms formed with bearings 4 and 5 in which a horizontal shaft 6 is mounted to be freely rotatable. The shaft 6 is provided with a shoulder 7 and with a grinding disc 8 of abrasive material in contact therewith. Furthermore, two nut rings 10 and 11 are screwed upon a threaded portion of the shaft and are bearing against a pulley 9 to press the latter against the grinding disc 8 whereby the same is kept in frictional engagement with the shoulder 7 and the disc 8 for common rotation.

In the recessed central part of frame 1 an auxiliary guide 12 is arranged and kept in place by means of a bolt 13' to adjustably accommodate a carrier 13 carrying a blade holder 17, 18, 20. The carrier 13 is displaceable in longitudinal direction and may be arrested in any desired position by means of clamping screws 14 and 14'. The ends of carrier 13 are formed with upwardly projecting arms having two pointed screws 15 and 16 inserted in axial registry. These screws serve to pivotally support a block 17 and to keep the latter in a predetermined position.

Attached to block 17 is an upwardly projecting spring leaf 20 carrying at its upper end a second block 18 which is integral with an upwardly projecting blade holder part 19 cooperating with another blade holder part 21 hinged to block 18 by means of a pivot 22 (Fig. 3). Both blade holder parts are adapted to keep between them a razor blade 23 such as shown in Fig. 4, and are for this purpose provided with a bolt 51 attached to the part 19 and projecting through a hole provided in part 21 to receive a clamping nut 24. Furthermore, the part 19 is provided with two pins 25 and 25' projecting through registering openings in part 21. The blade 23 is slipped with its holes 52 and 52' over these pins and, then, part 21 is folded over the blade and pressed thereupon by the nut 24 which is applied to the bolt 51. Thus it will be seen, that the razor blade 23 is kept in upright operative position relative to the grinding wheel.

Furthermore, a blade support is arranged on frame 1 to bear against the rear face of the edge to support the latter. As a part of the supporting face of the support is ground away in each cycle of operation, the support is preferably shiftable in the direction of its supporting face whereby successive portions of its surface may be brought into contact relation to the blade.

In the embodiment shown, the support is, for this purpose, formed by a rotatable cylinder 29 of soft steel or the like having its periphery in supporting relation to the blade, so that by rotation its circumference is shifted 70 in the direction of its supporting face. Opposite to the carriage 3 there is secured on frame 1 by means of screws 26' a standard 26 which has two upwardly projecting arms formed with bearings 27 and 27' accomodating a shaft 28 which is parallel to shaft 6 and arranged at the same level. The shaft 28 carries the cylinder 29. This cylinder has a peripheral recess 30 serving to give the grinding disc an unobstructed and free access to the 80 edge of the razor blade 23, compare Fig. 4.

Mounted on and secured to shaft 28 is a cord pulley 31 provided with clutch teeth 32 adapted to engage registering recesses in the lateral face of the supporting cylinder 29. 85 The pulley is, furthermore, provided with worm gear teeth 33 engaging a worm 34 carried by a vertical shaft 46 rotatable in a suitable vertical bearing provided in the standard 26. On pulley 31 a cord 35 is wound having its one end attached thereto, at 31', and and having its other end hanging downwardly and provided with a weight 36.

The carriage 3 is formed with a downwardly directed projection 37 which is recessed to accomodate the end of a helical spring 38 bearing against an adjustable screw 39 inserted in the front wall of frame 1 and permitting of an adjustment of the pressure exerted by the spring on the carriage 3 which 95 is pressed towards the right and thus kept in permanent engagement with a cam 40 mounted upon a horizontal cam shaft 41 journalled in frame 1 and continually subjected to a slow rotation by suitable driving means not shown in the drawings. On this shaft a second cam 42 is mounted having a projection 43 arranged to co-operate with a horizontal push rod 44 shiftably mounted in frame 1. In the course of each revolution of 100 shaft 41, this push rod is once shifted towards the right thereby engaging the one arm of a bell crank 45 freely swingably mounted upon the lower end of shaft 46. The other arm of the bell crank 45 carries a pawl 47 arranged 110 to engage a ratchet wheel 48 rigidly attached to shaft 46 and kept in engagement therewith by action of a spring leaf 49 bearing against the pawl. The bell crank 45 is kept in permanent contact with the push rod 44 by means of a tension spring 50 extended between a suitable projection of frame 1 and one arm of the bell crank. 120

The operation of the machine is as follows: 125 A rapid rotation in the direction of the arrow of Fig. 1 is imparted to the grinding disc 8 by a suitable belt (not shown) driving the pulley 9. Simultaneously, the cam shaft 41 is slowly rotated in clockwise direction. When the parts assume the position shown in 130

Fig. 1 the projection 37 is in engagement with the portion of cam 40 of smallest radius so that carriage 3 assumes its position nearest to, in fact in contact with, the supporting cylinder 29. In this position a cycle of operation has just been finished. In the course of the subsequent rotation of cam 40 through an angle of 90° the carriage 3 is moved towards its uttermost left point and the disc 8 is withdrawn from blade 23 permitting the blade holder 13 to be removed after a release of the clamping screws 14 and 14' and to be replaced by a similar spare holder provided with a new blank to be sharpened.

In the course of the further rotation of cam 40 through another 90° the grinding disc 8 slowly approaches the supporting cylinder 29. In the meantime, while the section of cam 40 of the largest radius entered in engagement with the projection 37 the portion 43 of cam 42 arrived in its operative position to the effect that the push rod was shifted and rocked the bell crank 45 whereby the ratchet wheel 48 was advanced by one tooth. A corresponding turn has been imparted to worm 34 and to the supporting cylinder 29. When the section 43 has moved past the push rod 44 the latter and the bell crank are restored to their normal position by action of the tension spring 50. The purpose of the turn of the cylinder 29 preparatory to a new cycle will be later explained.

In the course of the rotation of cam 40 through the third quarter of a revolution the carriage 3 is gradually advanced towards the support 30 and the new razor blade in contact therewith until the latter is engaged by the grinding disc 8 and is sharpened by the latter and transformed into a nearly finished condition requiring but a slight polishing treatment, whereupon a new cycle of operation is initiated.

In order to reset the grinding machine for the subsequent operation, the blade holder 13 is removed upon a sufficient release of the clamping screws 14 and 14' and is replaced by a spare blade holder which contains a new blank and is fixed in place by re-tightening the screws or bolts 14 and 14'. This replacement of the blade holder is to be effected during the period of the return of the carriage 3 toward its left end position under action of the cam 40 which is driven at so low a speed as will afford the time required for such replacement.

In Fig. 5 we have diagrammatically illustrated the successive stages of the operation. In this figure the reference numeral 8 designates the grinding disc and I to V designate five successive positions of the grinding disc assumed in the course from its outermost position I to its innermost position V in which the advance is completed and another cycle of operation is started. 23 illustrates a razor blade, the finished profile of which

is confined by the corner points A, N, L, D, E while the original form of the blank as it is inserted in the blade holder, is indicated by the points A, B, C, D, E. It will be observed that the blank is formed by a blade having a finished back C, D, E, and an unfinished front A, B which is to be ground to produce the front face N, L of the edge. 29 is the supporting cylinder, the peripheral face of which serves to support the rear face of the edge and, for this purpose, is kept in intimate contact therewith and stationary thereto during the grinding process.

As heretofore mentioned, the supporting cylinder is provided with a peripheral recess extending between the points K, L, Fig. 5. This recess is increased in circumferential length in the course of the operation on account of the stepwise turn imparted to the support 29. Its original shape is designated by the letters K, I, O and is increased in every cycle by an amount corresponding to the angle α by which the supporting cylinder is advanced in clockwise direction preparatory to each grinding cycle. This, in the course of the cycle illustrated in Fig. 5 the recess will be enlarged by the distance G, L.

The recess K, I, O is generated by the grinding disc 8 cutting into the supporting cylinder in the course of the first cycle in which the grinding disc has been advanced until the edge L was situated in the central plane P of the razor blade so that a portion K, I, O, K was cut out of the cylinder. When subsequently to each cycle the supporting cylinder is turned through the angle α , the recess K, L is successively enlarged as each time another section G, H, L is cut out of the circumference until eventually the entire cylinder is used up and a new cylinder of the prescribed diameter must be substituted. The depth QR of penetration of the grinding disc 8 depends on the edge angle 2α of the razor blade which is to be produced. The larger this angle is to be made, the lower arranged must be the blade 23 with regard to the line S, T connecting the centers of the supporting cylinder 29 and grinding disc 8, and the more towards the right will be positioned the blade so that the grinding disc will deeper cut into the supporting cylinder 29 until the razor blade edge is situated in the central plane P.

When the grinding disc 8 approaches the position I on its way toward the supporting cylinder 29 a blank having its front in unfinished condition has been substituted for the razor blade finished in the preceding cycle. As soon as the position II has been reached the grinding process proper commences, the edge B of the blade being progressively cut away until the position III has been reached where the portion designated by the letters B, F, G, has been ground off.

In the course of this phase of the cycle the upper edge of the blade gradually approaches the point C, and coincides with the latter as soon as position III has been reached. The rear face C, D of the blank is preferably shaped to place the edge C beyond the central plane P for the purpose of compensating for differences in the level of the edges D, C of successive blades. In other words, as the edge C of one blade may be situated at a higher level than the edge C of another blade on account of small differences in shape, the cross-sectional profile with the points C and D on different sides of the central plane has been chosen.

While the grinding disc advances from its position III to the position IV, the portion C, F, M, G is cut away so that the edge of the razor blade gradually approaches the point G where it arrives at the time IV. During this period, however, the edge C freely extends through the space its back lacking any support whatsoever, so that a ridge of the width C, G will be formed. This ridge represents the rim leaf which yields under the pressure of the grinding disc and is bent out of the way of the latter on account of its reduced thickness and tenderness. In the moment, however, position IV is reached, the grinding disc begins to operate upon a marginal zone confined by the edge G of the razor blade which is supported by portion G, C, D of the supporting cylinder 29 and, for this reason, cannot yield to the grinding pressure. Consequently, the advancing grinding disc engages the root of the ridge leaf which is bearing against the supporting cylinder 29 and as a result of the frictional engagement with the grinding disc is abruptly torn off. While the grinding disc advances from IV to V it exerts a unitary grinding action on the supporting cylinder and the razor blade simultaneously cutting away the portions G, M, N, L of the blade and G, H, L, of the supporting cylinder. In the course of this stage of the grinding process the edge gradually advances from G to L and, in this phase, another ridge cannot be formed because the edge is continually supported while it is subjected to the grinding pressure. Hence, it will appear that as soon as, or even before, the point L is reached, the edge will be perfectly sharp and free from any ridge so that any subsequent treatment of the razor blade with a view to removing a ridge is rendered superfluous.

The faces NL and LD are truly concave in the immediate proximity of the edge and are thereby distinguished from the razor blades produced by known methods in which the edge is deformed by bending stresses and subjected to a polishing treatment which removes material near the edge and thereby distorts the ground concave face transforming it in the immediate proximity of the edge into a

plane face or even into a convex face. Thus it is obvious that our novel machine permits of saving the time which was spent prior to our invention in removing the ridge from the edge and that the latter owing to the materially reduced polishing step is not so liable to be adversely affected by the development of heat or by mechanical stresses exerted by the polishing tool.

It might be suggested that it would appear sufficient to turn the supporting cylinder 29, preparatory to the grinding phase, with the edge of its recess up to the point L only rather than up to the point G inasmuch as the ridge is removed in the moment the contact of the supporting cylinder and the grinding disc occurs, which occurrence might just as well be postponed until the edge has advanced to L. In this case a simple support having the form of a simple plate of the profile U, V, L, W, Y would do as this plate would not be consumed and, for this reason, would not necessitate any replacement. It is to be observed, however, that in this case the operation would be finished in the moment the ridge leaf is torn away. This tearing off, however, always occasions small irregularities and recesses on the edge so that the latter does not comply with the requirements of uttermost exactitude and does not satisfy the demands for a perfect razor blade.

Besides, the unavoidable wear of the grinding disc accounts for a certain irregularity of the final position of the razor blade edge which, accordingly, does not always exactly coincide with point L of the supporting cylinder. It follows that, while a perfect grinding disc could perhaps be adjusted to always exactly reach the position V thereby removing the ridge even with a simple support plate U, V, L, W, Y, under ordinary conditions, for instance with a worn grinding disc, the position V would sometimes not exactly be reached so that a ridge leaf would be left. For this reason we advance the grinding disc beyond the position IV thereby cutting into the support 29. This operation compensates for the unavoidable small deviations in the movements of the elements of the machine which even with a perfect grinding disc could never be entirely eliminated. In view of these considerations we prefer, in favor of reasonable requirements regarding the exactness of the elements of the machine, to provide, as it were, a safety coefficient with regard to the supporting action, in that we support the rear face of the edge beyond the point L marking the final location of the finished cutting edge, and in that we partially cut away this supported zone together with its support while the grinding disc approaches its innermost position. The portion of the support cut away in each cycle must, of course, be replaced preparatory to the subsequent cycle.

By the machine heretofore described a cutting edge is obtained which is sharp and without any ridge, regardless of whether or not the elements of the machine operate quite accurately and whether the final edge exactly coincides with the point L in the central plane P.

Obviously, the requirement of replacing the cut-away portion of the support prior to every cycle may be complied with in a great variety of constructions. We prefer, however, to use a supporting cylinder such as heretofore described as in this manner the replacement after each cycle may be accomplished in an extremely simple manner by turning the cylinder until its edge G confining the recess has been moved beyond the location of the final blade edge by such an amount as safety compensates for the effects of possible inaccuracies of the machine.

In producing the rear face C, D of the razor blade a similar method of supporting the back of the blade need not be employed, it being sufficient to support the original blank having the profile A, B, Z, E by a small support blade Z, A', B', C', as in this case the configuration of the edge D' is without any consequence so that the formation of a ridge does not matter. The function of the support in this case would simply be to prevent the blade which is given the profile AND'ZE from being sprung out of shape. It may be mentioned that this preparatory stage does not form part of our invention and that the profile AND'ZE may be produced in any suitable manner before the blade is sharpened with our novel machine.

An essential requirement for the efficient operation of our machine is an intimate contact of the supporting cylinder with the rear face of the blade edge or at least with the zone confined by the final edge. In order to avoid unreasonable requirements regarding the accuracy of the adjustment of the blade holder, the latter is preferably of yielding properties. In the embodiment shown for instance, it includes in its structure a spring leaf 20 permitting a small flexion vertical to its plane as well as a small turn about its vertical axis.

In adjusting the blade, we first align the blade edge in the desired level parallel to the axis of the supporting cylinder and, subsequently, somewhat release one of the pointed screws 15 or 16, whereupon we turn the entire blade holder about the axis 15, 16 to bring the blade in full contact with the supporting cylinder. Then, the released pointed screw is tightened again so as to arrest the block 17. On account of this adjustment the rear face of the blade edge is bearing against the supporting cylinder with a slight pressure while the spring leaf 20 is slightly bent to produce such pressure. This will also be the case, if blades of a slightly different size

are inserted as the flexibility of the spring leaf 20 compensates for small differences between the shape of the individual blades. The blade holder, however, will be subject to small deviations from its vertical position. If it stands forwardly inclined with regard to its normal position, the point D of the rear face is liable to come into contact with the periphery of the supporting cylinder instead of the point G so that the final edge would not be supported. This may obviously be avoided by dimensioning the radius of the supporting cylinder slightly smaller than the radius of the curvature of the profile section C, E or, in other words, than the radius of the grinding disc employed in producing the rear face of the blade. In this manner, of course, a perfect contact over the entire surface of the rear face C, D is obviated, but an efficient support of that zone is secured in which the final edge is situated and this is what counts. In dimensioning the diameter of the supporting cylinder unavoidable inaccuracies and differences of the individual blades are to be taken in consideration. The diameter must be made smaller than is the diameter of the grinding disc producing the rear profile when it is worn off.

In the moment the position IV has been reached, the grinding disc engages the periphery of the supporting cylinder tending to turn the same in clockwise direction. Such a turn, however, is liable to occur inasmuch as the cylinder moves in the same direction when it is turned through the angle α preparatory to every cycle so that the back-lash in the turning mechanism is just in the sense which would permit of such a rotation unless particular precautions were taken. Any turn of the supporting cylinder during its engagement with the grinding disc, however, would cause the latter to jam or perhaps even to crack. For this reason, means must be provided which obviate a back-lash in the driving gear of the supporting cylinder. This may be achieved in the simplest manner by causing the driving members to be in permanent contact with each other in a sense contrary to their driving effect. For this purpose we have provided the weight 36 which subjects shaft 28 to a torque of the same sense as that produced by the engaging grinding disk. This torque causes the teeth of the worm gear 33 to keep contact with the thread of the self-locking worm 34 whereby the supporting cylinder is prevented from being turned by the grinding disc. It follows that the advance of the supporting cylinder through the angles α is, exactly speaking, performed by action of the weight 36 rather than by the worm gear 34, 33 which really merely determines the exact degree of such advance.

What we claim is:

1. A blade sharpening machine comprising a grinding element, a support, a blade holder

- to keep a blade therebetween in grinding position and in contact with said support, the latter being adapted to be kept stationary during the grinding cycle and to be advanced between successive cycles in the direction of its supporting face whereby successive portions of its surface may be brought into contact relation to said blade for successive cycles of operation.
- 10 2. In a blade sharpening machine, the combination comprising a blade support, a rotating grinding wheel, means to move the wheel towards said support to such an extent that a portion of the support is ground away, and a blade holder associated with said support to keep a blade stationary relative to said support and in intimate contact with the portion cut away, while the blade is being ground.
- 15 3. In a blade sharpening machine, the combination comprising a blade support, a rotating grinding wheel, means to reciprocate said wheel to and from said blade support, means associated with the support to advance the support step by step into the path of said grinding wheel in synchronism with the reciprocation of the same, whereby a portion of said support is ground off in the course of each stroke of said grinding wheel, and a blade holder adapted to keep a blade stationary relative to said support and with its rear marginal zone in intimate contact with said portion for the purpose of subjecting its front to the action of said grinding wheel while its edge is supported by said portion.
- 20 4. A blade sharpening machine comprising a frame, a carriage slidably arranged thereon, a rotating grinding disc mounted on said carriage and having its axis transverse to the direction of movement of said carriage, a blade-supporting cylinder mounted on said frame in opposition to said grinding disc and having its axis parallel to the axis of said disc, means to reciprocate said carriage to cause said grinding disc to cut into said cylinder, and a blade holder arranged between said disc and said cylinder and adapted to keep a blade in upright position with its marginal portion in contact with said cylinder and in the path of said disc.
- 25 5. A blade sharpening machine comprising a frame, a carriage slidably arranged thereon, a rotating grinding disc mounted on said carriage and having its axis transverse to the path of said carriage, a blade-supporting cylinder mounted on said frame in opposition to said grinding disc and having its axis parallel to the axis of said disc, means to reciprocate said carriage to cause said grinding disc to cut into said cylinder, means to turn said cylinder about its axis through a definite angle once at each reciprocation of said carriage, and a blade holder arranged between said disc and said cylinder and adapted to keep a blade in upright position with its marginal portion

ginal portion in contact with said cylinder and in the path of said disc.

6. The combination set forth in claim 4, in which said blade holder comprises an upright spring leaf and a clamping device attached to the upper end thereof and adapted to receive a razor blade.

7. In a blade sharpening machine, the combination comprising a non-resilient and non-abrasive support, a blade holder arranged to keep a blade with a marginal face in contact with a portion of said support, a grinding wheel mounted for relative movement toward and from said blade-contacting portion of said support, the extent of said movement being sufficient for said grinding wheel to cut into said portion while sharpening the supported edge of the blade, means to mount said support for a movement which will bring another portion of it into contacting relation with a blade after said first-mentioned portion has been ground off, and means for maintaining said support in position relative to said grinding wheel against the grinding pressure exerted by the latter.

8. In a blade sharpening machine, the combination comprising blade supporting means of non-resilient and non-abrasive material, a rotating grinding wheel, means for reciprocating said wheel in the direction to and from said supporting means, means associated with said supporting means for intermittently advancing said supporting means into the path of said grinding wheel in synchronism with the reciprocation of the same, whereby a portion of said supporting means will be ground off in the course of each forward stroke of said grinding wheel, and a blade holder adapted to keep a blade stationary relative to said support and with its one marginal face in intimate contact with said portion for the purpose of subjecting its other marginal face to the action of said grinding wheel while the very edge of the blade is supported by said portion.

9. A blade sharpening machine comprising a frame, a carriage slidably arranged thereon, a rotating grinding disc mounted on said carriage and having its axis horizontal and transverse to said carriage, a blade supporting body of non-abrasive and non-resilient material mounted on said frame in opposition to said grinding disc, means to reciprocate said carriage to cause said grinding disc to cut into said body, and a blade holder arranged between said disc and said body and adapted to keep a blade in upright position with its marginal portion in contact with said body and in the path of said disc to be ground off simultaneously with said body.

10. In a blade sharpening machine, the combination comprising a non-resilient and non-abrasive support having a rectilinear portion dimensioned to support the marginal

face of a razor blade along its entire edge, a blade holder associated therewith to keep a blade stationary relative to, and in intimate contact with said portion of the support, a grinding wheel and means to move said wheel towards said support and said blade such a distance that contacting portions of the blade and said support are simultaneously ground away.

10 In testimony whereof we affix our signatures.
